DESIGN FOR A PNEUMATIC TIRE

Elliott S. Ewart, St. Clair Shores, Mich., assignor
to United States Rubber Company, New York,
N. Y., a corporation of New Jersey

Application July 4, 1945, Serial No. 120,525

Term of patent 14 years

(Cl. D90—20)

To all whom it may concern:

Be it known that I, Elliott S. Ewart, a citizen of the United States of America, residing in St. Clair Shores, county of Macomb, and State of Michigan, have invented a new, original, and ornamental Design for a Pneumatic Tire, of which the following is a specification, reference being had to the accompanying drawing, forming part thereof, wherein:

Fig. 1 is a plan view of a portion of a pneumatic tire embodying my new design;

Fig. 2 is a fragmentary side elevational view thereof; and,

Fig. 3 is a transverse view, in section, taken along lines III—III of Fig. 1.

I claim:

The ornamental design for a pneumatic tire, as shown.

ELLIOTT S. EWART.
